DESIGN FOR A FOUNTAIN PEN OR SIMILAR ARTICLE

Anatol N. Andrews, Los Angeles, Calif.

Application July 1, 1938, Serial No. 78,222

Term of patent 14 years

To all whom it may concern:

Be it known that I, Anatol N. Andrews, a citizen of the United States, residing at 1435 West 25th Street, city of Los Angeles, in the county of Los Angeles and State of California, have invented a new, original, and ornamental Design for Fountain Pens or Similar Articles, of which the following is a specification, reference being had to the accompanying drawing, forming part thereof.

Fig. 1 is a side elevational view of a fountain pen in an open position showing my new design; and Fig. 2 is a side elevational view of the same in a closed position at right angles to the disclosure in Fig. 1.

I claim:

The ornamental design for a fountain pen or similar article, as shown.

ANATOL N. ANDREWS.
